US00D616389S

(12) **United States Design Patent**
Takahashi

(10) **Patent No.:** US D616,389 S
(45) **Date of Patent:** ** May 25, 2010

(54) **VACUUM CONTACT PAD**

(75) Inventor: **Tamami Takahashi**, Ohta-ku (JP)

(73) Assignee: **Ebara Corporation**, Tokyo (JP)

(**) Term: **14 Years**

(21) Appl. No.: **29/335,608**

(22) Filed: **Apr. 17, 2009**

(30) **Foreign Application Priority Data**

Oct. 20, 2008 (JP) 2008-026899

(51) **LOC (9) Cl.** 13-03

(52) **U.S. Cl.** D13/182

(58) **Field of Classification Search** D13/182;

257/48; 269/21; 279/3; 438/106, 584; 451/388

See application file for complete search history.

(57) **CLAIM**

The ornamental design for a vacuum contact pad, as shown and described.

DESCRIPTION

FIG. 1 is a front elevation view of a vacuum contact pad showing our new design, the rear view being a mirror image thereof;

FIG. 2 is a right side elevation view, the left side being a mirror image thereof;

FIG. 3 is a top plan view thereof;

FIG. 4 is a bottom plan view thereof;

FIG. 5 is a perspective view thereof;

FIG. 6 is a partial enlarged perspective view thereof; and,

FIG. 7 is a perspective view showing the usable state thereof.

The broken line showing of the environment is for illustrative purposes only and forms no part of the claimed design.
